REFRIGERATION

Harry K. Bergholm, Stockholm, Sweden, assignor,
by mesne assignments, to Servel, Inc., New
York, N. Y., a corporation of Delaware

Application December 19, 1939, Serial No. 309,969
In Germany December 22, 1938

9 Claims. (Cl. 62—119.5)

My invention relates to refrigeration and more particularly to a refrigeration system employing evaporation of refrigerant fluid in the presence of an inert gas or auxiliary agent.

In apparatus of this type it is customary to provide a gas heat exchanger for exchanging heat between cold gas flowing from an evaporator to an absorber and warm gas flowing to the evaporator from the absorber. In many instances the heat exchanger is arranged so that it extends through the wall of a refrigerator cabinet. In order to obtain the greatest possible cooling effect from the relatively cool gas flowing from the evaporator, it is preferable to connect the heat exchanger in such a manner that this gas flows in contact with the outer wall of the exchanger. With this arrangement the portion of the heat exchanger within the refrigerator cabinet aids in effecting space cooling. The portion of the heat exchanger outside of the cabinet is, however, contacted by atmospheric air and there is a tendency for water vapor contained in such air to condense on the relatively cold outer surface of the heat exchanger. Any condensation forming on the portion of the heat exchanger outside the cabinet is objectionable.

In accordance with the invention I provide a jacket around the portion of the gas heat exchanger disposed outside of the refrigerator cabinet and supply this jacket with relatively warm gas flowing from the absorber. The jacket may also surround a portion of the conduit through which cold gas is conducted from the heat exchanger to the absorber. With this arrangement atmospheric air does not contact relatively cold parts of the refrigeration apparatus outside of the cabinet whereby condensation of water vapor is avoided. A further advantage resulting from this arrangement is that increased heat transfer surface is provided between the warm and cold gases so that the efficiency of the apparatus is improved. Further, the warm absorption liquid flowing from the generator to the absorber may be arranged to flow in thermal relation with the jacket, whereby heat transfer is effected between the liquid and the cold gas flowing from the evaporator.

The above and objects and advantages of the invention will be more fully understood upon reference to the following description and accompanying drawings forming a part of this specification, and of which:

Fig. 1 more or less diagrammatically illustrates 55

refrigeration apparatus embodying the invention; and

Fig. 2 illustrates another embodiment of the invention. Referring to Fig. 1, a generator 10 includes a flue 11 surrounded by a jacket 12. The flue 11 is arranged to be heated in any suitable manner, as by the gas burner 13. A conduit 14 connects the upper part of jacket 12 with the lower end of a rectifier 15, the other end of which is connected to the upper end of a condenser 16. The lower end of condenser 16 is connected to a conduit 17 which extends through the insulated wall 18 of a refrigerator cabinet and communicates with the upper end of an evaporator 19 which is disposed within the cabinet.

The evaporator shown is in the form of a pipe coil, the lower end of which is connected by a conduit 20 with a space 21 formed within one end of a gas heat exchanger 22. The gas heat exchanger 22 includes an outer shell 23 which is closed at one end by a header 24. A plate 25 is disposed within the shell adjacent to the header 24 and forms one wall of the space 21. A plate 26 is disposed at the other end of the shell, and a plurality of tubes 27 extend through the plates 25 and 26. A jacket 28 is arranged around the portion of shell 23 which extends within and through the insulated wall 18. As shown in Fig. 1, the tubes 27 connect the space 21 with the interior of jacket 28.

A conduit 29 connects the upper end of the evaporator with the space 30 formed within the shell 23 between the plates 25 and 26 and outside of the tubes 27. A drain conduit 9 is connected to the lower part of the evaporator and to the space 30. A conduit 31 extends downwardly from the other end of space 30 and communicates with a vessel 32. The jacket 28 is provided with a downwardly extending leg or auxiliary jacket 33 which surrounds a portion of conduit 31.

The lower end of absorber 34 is connected to the upper part of vessel 32, and the upper end of the absorber is connected by a conduit 35 with the leg 33. A conduit 36 connects the lower part of vessel 32 with the inner passage 37 of a liquid heat exchanger 38. The other end of the inner passage is connected to the bottom of a coil 39 arranged in heat exchange relation with the flue 11. A conduit 40 connects the upper end of coil 39 with the upper part of the generator 10. A conduit 41 connects the lower part of the generator with the outer passage 42 of the liquid heat exchanger 38. A conduit 43 connects the other end of pipe 42 with the upper part of the absorber 34.

A pressure vessel 44 is connected to the condenser 16 and to the gas circuit in a manner well known in the art, whereby the total pressure in the apparatus is increased with increase in air temperature to insure condensation of refrigerant vapor in the condenser. As shown, a conduit 45 connects the lower end of condenser 16 with one end of vessel 44, and a conduit 46 connects the other end of vessel 44 to conduit 31 of the gas circuit.

The operation of the above described device is as follows:

The generator 10 contains a solution of refrigerant in absorption liquid, such as ammonia in water, for example, and also an inert gas, such as hydrogen. Heating of generator 10 by burner 13 causes expulsion of refrigerant vapor from solution. The refrigerant vapor flows upwardly through the conduit 14 to the rectifier in which any vapor of absorption liquid accompanying refrigerant vapor is condensed and flows back to generator 10. Refrigerant vapor is liquefied in condenser 16 and the liquid flows through conduit 17 into the upper part of the evaporator 19.

Inert gas enters the lower part of evaporator 19 through conduit 20 and flows upwardly and counter-current to liquid refrigerant. Liquid refrigerant evaporates and diffuses into inert gas to produce a refrigerating effect with consequent absorption of heat from evaporator 19 and its surroundings.

The resulting mixture of refrigerant and inert gas, that is, gas rich in refrigerant, flows from evaporator 19 through conduit 29 into space 30 in gas heat exchanger 22. The rich gas mixture cools shell 23 whereby heat is abstracted from the space within the cabinet. From the space 30 the rich gas mixture flows through conduit 31 and the upper part of a vessel 32 into the lower end of absorber 34. Absorption liquid weak in refrigerant enters the upper part of absorber 34 through conduit 43 and flows downwardly through the absorber. The absorption liquid absorbs refrigerant vapor from the inert gas, and inert gas weak in refrigerant flows upwardly through conduit 35.

Heat is liberated with absorption of refrigerant vapor in absorber 34, so that the inert gas flowing from absorber 34 through conduit 35 is relatively warm. The warm weak gas flows through the leg 33 into the main part of jacket 28, and thence through the tubes 27, space 21 and conduit 20 into the lower part of evaporator 19. Since the portion of gas heat exchanger 22 outside of the cabinet 18 is surrounded by the jacket 28, atmospheric air cannot come in contact with relatively cold portions of the heat exchanger. No condensate forms on jacket 28 because the inner surfaces of the outer walls are contacted by warm gas flowing from absorber 34. The leg 33 or extension of jacket 28 prevents atmospheric air from contacting the upper part of conduit 31. By the time the rich gas mixture reaches the lower part of conduit 31 not enveloped by leg 33, its temperature has been raised sufficiently by heat exchange with warm gas in the jacket so that condensation thereon is avoided.

Absorption liquid enriched in refrigerant flows from the lower part of absorber 34 into vessel 32, and thence through conduit 36 and inner passage 37 of liquid heat exchanger 38 into the lower end of coil 39. Liquid is raised by thermosiphon tube 40 into the upper part of generator 10. The refrigerant vapor expelled out of solution from generator 10, together with refrigerant vapor en-

tering through thermosiphon tube 40, flows upwardly to condenser 16, as explained above.

The absorption liquid from which refrigerant has been expelled flows from generator 10 through conduit 41, outer passage 42 of liquid heat exchanger 38, and conduit 43 to the upper part of absorber 34. This circulation of absorption liquid results from the raising of liquid by thermosiphon tube 40.

10 The circulation of gas in the gas circuit described above is due to the difference in specific weight of the columns of rich and weak gas formed by gas flowing toward and away from absorber 34. Since the rich gas is heavier than the weak gas, a force is developed or produced for causing circulation of the gas.

The embodiment illustrated in Fig. 2 is generally similar to that shown in Fig. 1 and differs therefrom in that the leg 33a of jacket 28 extends downwardly around the conduit 31 to a point below the upper end of absorber 34. Also, the conduit 43 is connected to the lower end of jacket 28 so that a pool of relatively warm absorption liquid is formed in the lower end of the jacket. With this arrangement weak absorption liquid from generator 10 first flows in heat exchange relation with rich gas in conduit 31 and thence into the upper end of absorber 34.

Not only is a greater portion of the conduit 31 enclosed within a heating jacket in the embodiment of Fig. 2, but heat exchange is also effected between the weak absorption solution flowing from the generator to the absorber and the rich gas mixture flowing from the evaporator to the absorber.

In other respects the embodiment of Fig. 2 is like Fig. 1 with similar parts referred to by the same reference numerals, and further description thereof will not needlessly be repeated here.

40 While several embodiments of the invention have been shown and described, such variations and modifications are contemplated as fall within the true spirit and scope of the invention, as pointed out in the following claims.

What is claimed is:

1. A refrigerator having a thermally insulated storage space, refrigeration apparatus including an evaporator arranged in thermal transfer relation with said space and in which refrigerant evaporates in the presence of an inert gas, means including a gas heat exchanger having an inner passage to provide a first path of flow for conducting gas to said evaporator and an outer passage to provide a second path of flow for conducting gas from said evaporator, a part of said gas heat exchanger being outside said space, and structure providing an enclosure about the portion of the outer passage of said heat exchanger disposed outside said space, said enclosure forming a part of the first path of flow through which gas is conducted to said evaporator.

2. A refrigerator having a thermally insulated storage space, refrigeration apparatus containing a plurality of fluids and including an evaporator in which refrigerant fluid evaporates in the presence of an auxiliary fluid, said evaporator being arranged in thermal relation with said space, means providing a first path of flow for gas flowing to said evaporator, means providing a second path of flow for gas flowing from said evaporator, a part of said second means being disposed within a part of said first means to form a heat exchanger, a part of said heat exchanger being disposed outside said space, structure forming an enclosure about the part of said

heat exchanger outside said space, and means to circulate warm fluid in the system through said enclosure.

3. In an absorption refrigerating apparatus, a refrigerator cabinet having thermally insulated walls, an evaporator disposed within said cabinet, a gas heat exchanger extending through one of said walls, said heat exchanger including an outer shell, means connecting said shell to the outlet of said evaporator whereby cold gas is supplied to the space within said shell, an absorber disposed outside said walls, a jacket around the portion of said shell outside said walls, and means for supplying warm gas from said absorber to said jacket.

4. In an absorption refrigeration apparatus, a refrigerator cabinet having thermally insulated walls, an evaporator disposed within said cabinet, a gas heat exchanger extending through one of said walls, said heat exchanger including an outer shell and an inner conduit, means connecting said shell to the outlet of said evaporator whereby cold gas is supplied to the space within said shell and around said conduit, an absorber disposed outside said walls, a jacket around the portion of said shell outside said walls, means for supplying warm gas from said absorber to said jacket, one end of said conduit being connected to said jacket to receive gas therefrom, and means for conducting gas from the other end of said conduit to the inlet of said evaporator.

5. In an absorption refrigerating apparatus, a refrigerator cabinet having thermally insulated walls, an evaporator disposed within said cabinet, a gas heat exchanger extending through one of said walls, said heat exchanger including an outer shell, means connecting said shell to the outlet of said evaporator whereby cold gas is supplied to the space within said shell, an absorber disposed outside said walls, a conduit connecting said shell with the gas inlet of said absorber, a jacket around the portion of said heat exchanger outside said walls and around at least a portion of said conduit, and means for supplying warm gas from said absorber to said jacket.

6. In an absorption refrigerating apparatus, a refrigerator cabinet having thermally insulated walls, an evaporator disposed within said cabinet, a gas heat exchanger extending through one of said walls, said heat exchanger including an outer shell, means connecting said shell to the outlet of said evaporator whereby cold gas is supplied to the space within said shell, an absorber disposed outside said walls, a conduit connecting said shell with the lower end of said absorber, a jacket around the portion of said shell outside said walls and around at least a portion of said conduit, the upper end of said absorber being connected to said jacket whereby warm gas is supplied to said jacket, a generator, and means

for supplying warm liquid from said generator to said jacket, whereby the liquid is supplied to the upper end of said absorber.

7. In an absorption refrigerating apparatus, a refrigerator cabinet having thermally insulated walls, an evaporator disposed within said cabinet, a gas heat exchanger extending through one of said walls, said heat exchanger including an outer shell and an inner hollow element, means connecting said shell to the outlet of said evaporator whereby cold gas is supplied to the space within said shell and around said inner element, an absorber disposed outside said walls, a conduit connecting said shell with the gas inlet of said absorber, a jacket around the portion of said shell outside said walls and around at least a portion of said conduit, the upper end of said absorber being connected to said jacket whereby warm gas is supplied to said jacket, one end of said hollow element being connected to said jacket to receive gas therefrom, means for conducting gas from the other end of said element to said evaporator, a generator, and means for supplying warm liquid from said generator to said jacket, whereby the liquid is supplied to the upper end of said absorber.

8. In an absorption refrigerating apparatus, a refrigerator cabinet having thermally insulated walls, an evaporator disposed within said cabinet, a gas heat exchanger extending through one of said walls, said heat exchanger including an outer shell, means connecting said shell to the outlet of said evaporator whereby cold gas is supplied to the space within said shell, an absorber disposed outside said walls and below said heat exchanger, a conduit having vertical extent connecting said shell with the lower end of said absorber, a jacket around the portion of said shell outside said walls and having a downwardly extending leg around at least a portion of said conduit, the upper end of said absorber being connected to said leg whereby warm gas is supplied to said jacket, a generator, and means for supplying warm liquid from said generator to said leg, whereby the liquid is supplied to the upper end of said absorber.

9. Refrigeration apparatus including an evaporator in which refrigerant evaporates in the presence of an inert gas and means for conducting gas to and from said evaporator including a gas heat exchanger, at least a part of which is exposed to atmosphere, and having an inner passage for conducting gas flowing to said evaporator and an outer passage to conduct gas flowing from said evaporator, and structure providing an enclosure about said portion of the gas heat exchanger exposed to atmosphere and forming a part of a path of flow for gas to said inner passage.

HARRY K. BERGHOLM.
